UNITED STATES PATENT OFFICE.

LEE HOWARD SIMMONS, OF GOLDSBORO, NORTH CAROLINA, ASSIGNOR TO SIMMONS MANUFACTURING COMPANY, OF WILMINGTON, NORTH CAROLINA, A CORPORATION OF NORTH CAROLINA.

CENTER REST BAR FOR BOILER GRATES.

1,416,131.

Specification of Letters Patent. Patented May 16, 1922.

Application filed March 21, 1921. Serial No. 454,135.

To all whom it may concern:

Be it known that LEE HOWARD SIMMONS, a citizen of the United States, residing at Goldsboro, in the county of Wayne and State 5 of North Carolina, has invented certain new and useful Improvements in Center Rest Bars for Boiler Grates, of which the following is a specification.

My invention relates to a new and useful 10 improvement in center rest bars for furnace grates and especially to a rest bar to be used with grates that are installed under the boilers of locomotives.

The rest bars for furnace grates used in 15 locomotives must be exceedingly strong due to the hard usage to which they are naturally subjected. Furthermore the bars must be exceedingly strong as if they should break while the locomotive is in use the grate would 20 drop, causing serious delays, especially if the locomotive be a great distance from the shops.

It is the general practice to make these 25 rest bars for locomotive grates of steel and to widen the under portion so as to procure as strong a bar as possible. Rest bars therefore as used in locomotive boiler grates are very heavy and naturally relatively expensive.

Cast iron bars are cheaper to manufacture 30 but due to the heat and to the strain they are likely to break or fracture and drop the grate so that heavy steel ones now are generally in use.

One of the objects of the present invention 35 is to provide a center rest bar, the major portion of which is formed of cast iron and to provide what might be termed a cradle of steel for supporting the rest bar, which 40 cradle is riveted or otherwise secured to the bar so that it is for practical purposes an integral part of the same.

Still other objects of my invention are to 45 provide a center rest bar, the greater portion of which may be formed of the cheaper material, iron; to provide end pieces of steel and to provide two further strips of steel which are placed along the lower edges of the rest bar, the iron portion of the bar being 50 cut away throughout its length at its lower portion so that the steel strips will fit under the ledges or flanges thus formed in the iron portion of the rest bar.

With these and other objects in view the 55 invention consists in certain new and novel

structures and combination of parts as may be hereinafter more fully described and pointed out in the claims.

In the drawings showing a preferred form,

Fig. 1 is a side elevation of the improved center rest bar, a portion of one steel strip being broken away for the sake of clearness.

Fig. 2 is an end view of the same.

Fig. 3 is a sectional view on line 3—3 of 65 Fig. 1, and

Fig. 4 is a perspective of one of the end supporting pieces.

At the outset, it may be said that locomotives grates are generally formed of two 70 series, which grates are placed transversely of the locomotive, the outer ends of the grates resting on the supporting frames and the inner adjacent ends of the grates resting on what is known as a center rest bar, and it is 75 to this bar that the present invention relates.

Referring now to the drawings there will be seen the major portion 1 of the center rest bar, the one end being slightly angular as at 80 2, as is common to a center rest bar. This major portion of the rest bar is formed of cast iron which of course is relatively cheaper per pound than steel, of which material rest bars are generally formed. The 85 opposite ends of this bar are undercut as at 3 and placed thereunder are the end pieces 4 which are formed of high grade steel. Each end piece has an angular top surface 5 to correspond with the undercut portion 3 90 of the grate bar and is also cut out as at 6 to form the bearing surface 7 which will rest on a plate or lug of the grate support, (not shown). A plurality of holes 8 are shown in this end piece for the reception of rivets 9. 95

Referring again to the major portion of the rest bar 1 it will be noticed that, extending throughout its length and at the lower portion and on its opposite sides, it is cut away as at 10 to form the upper flanges 11 100 and the reduced portion 12.

Placed along this reduced portion 12 and extending under the flanges 11 are the two strips of steel 13 which are greater in thickness than the width of the flanges 11 so that 105 these strips extend slightly outwardly beyond the sides of the major portion of the grate bar. These strips 13 are then securely riveted throughout their length as at 14 and their ends are securely riveted to the end 110

pieces 4 by the rivets 9 passing through the aforementioned holes 8, formed in these end pieces.

Also formed on the major portion 1 of the 5 grate bar are a plurality of lugs 15 on which the grates are to be supported when the rest bar is in position. These lugs of course being spaced as desired depending on the size and number of the grates.

10 From the foregoing it will be seen that I have formed a center rest bar, the major portion of which may be formed of cast iron which is in turn secured in a body of steel so that even should the major portion of the 15 grate bar 1 fracture or break in one or a number of places the steel strips 13 will support the same together with the end pieces 3 so that it will be impossible for the bar to drop and thus lower the grates.

20 Furthermore I have found in practice that a bar formed according to the foregoing description has a greater tensile strength than a bar of solid steel and weighs far less than one formed entirely of steel and of course 25 much cheaper to manufacture.

Furthermore the rest bar does not have to be enlarged on its under surface as do the all steel bars now in general use.

Having thus described my invention what 30 I claim as new and desire to secure by Letters Patent is:

1. A center rest bar comprising a main body portion of cast iron and having its opposite ends undercut, steel supporting end 35 members placed in the undercut portions, and steel reinforcing strips secured to the steel ends and to the outer opposite sides of the main body portion.

2. A center rest bar comprising a main body portion formed of cast iron and having its opposite ends undercut, two steel supporting end members fitting within the undercut portions, the body portion of said rest bar having cut out portions extending from 45 end to end thereof, two steel reinforcing strips fitting within said cut out portions and secured to the end members and to the body portion of said rest bar.

3. A center rest bar comprising a main body portion of cast iron and having its opposite ends undercut, two steel supporting end members placed in the undercut portions and said steel supporting end members each having a portion cut away to form a supporting flange, the main body portion 55 having a portion cut away on each side thereof to form an upper flange, two steel reinforcing strips placed beneath these flanges and of a greater thickness than the cut away portions in said main body portion, 60 said reinforcing strips extending from end to end of the body portion, riveted thereto and secured to the two steel supporting end members.

4. A center rest bar comprising a main 65 body portion of cast iron and provided with supporting lugs throughout its length, the ends of said main body portion being undercut and two steel supporting end members fitting snugly within said undercut portions, 70 the said main body portion being grooved from end to end on its opposite sides, two steel reinforcing strips occupying the said grooves and said strips being slightly greater in thickness than the depth of the groove 75 formed in the body portion of the rest bar and said strips being tightly secured to the main body portion and to the steel supporting end members.

5. A center rest bar having a main body 80 portion formed of cast iron and being angular in form at one end, lugs formed throughout the length of said main body portion, the opposite ends of the said main body portion being undercut, two steel supporting end 85 members secured in said undercut portions, said body portion being reduced along its lower edge and on its opposite sides to form flanges, steel reinforcing strips fitting under said flanges and secured to said supporting 90 end members and to each other, to thereby form a steel support extending from end to end of the said main body portion of the rest bar.

In testimony whereof I affix my signature. 95
LEE HOWARD SIMMONS.
